UNITED STATES PATENT OFFICE.

WILLIAM D. CHASE, OF POUGHKEEPSIE, NEW YORK, ASSIGNOR TO THE
POUGHKEEPSIE ART PULP COMPANY, OF POUGHKEEPSIE, NEW YORK,
A CORPORATION.

TRAVELING-CASE.

SPECIFICATION forming part of Letters Patent No. 758,170, dated April 26, 1904.

Application filed December 17, 1903. Serial No. 185,510. (No model.)

To all whom it may concern:

Be it known that I, WILLIAM D. CHASE, a citizen of the United States, residing at Poughkeepsie, in the county of Dutchess and State 5 of New York, have invented new and useful Improvements in Traveling-Cases, of which the following is a specification.

My invention relates to improvements in traveling-cases, and more particularly in that 10 type of traveling-cases commonly known on the market as "dress-suit" cases.

The object of my invention is to improve and simplify the construction of devices of this character, and thereby provide a case or 15 box which will possess great rigidity, strength, and durability and which may be manufactured at a comparatively small cost.

With this and other objects in view the invention consists of certain novel features of 20 construction, combination, and arrangement of parts, as will be more fully described, and particularly pointed out in the appended claim.

In the accompanying drawings, Figure 1 is 25 a perspective view of a dress-suit case constructed in accordance with my invention, the cover or lid of the same being partially raised to more clearly illustrate the construction. Fig. 2 is a transverse sectional view through the same, the cover being in its closed position. Fig. 3 is a detail sectional view, on an enlarged scale, taken through the beveled upper edge of the body of the case. Fig. 4 is a detail plan view of one corner of the body of 30 the case. Fig. 5 is a detail sectional view through the same.

Referring to the drawings by numerals, 1 denotes a dress-suit case of the usual form, comprising a rectangular body or box 2, having 35 an open top or face adapted to be closed by a hinged cover or lid 3. The sides 4 and ends 5 of the said body 2 are, as shown, constructed of outer and inner layers or thicknesses 6 and 7 of sheet material, preferably pasteboard or 50 jute-pulp board, between which, adjacent to their upper edges, is interposed an intermediate layer 8 of material, preferably sheet metal, such as tin. The metal sheet 8 and the

inner sheet 7 of pulp or pasteboard project above the upper edge of the outer pasteboard 50 sheet 6 and are bent inwardly, as at 9, to form a surrounding beveled edge 10 for the open top or face of the body 2. The extreme edges of said sheets 8 and 7 are folded or doubled together, as shown at 11, to form a strengthening rib or bead for the said beveled portion 55 10 and also to provide a finished edge for the same. The sheet of metal 8 may extend down to any desired extent between the inner and outer pasteboard sheets, and the said three 60 sheets or layers of material may be secured together in any suitable manner. It will be seen that the said sheet of metal forms an exceedingly durable and rigid rim for the open top or face of the body and that the down- 65 turned edges 12 of the hinged cover or lid 3 will rest securely and tightly upon said beveled rim to provide a simple and effective closure for the case.

From the foregoing description, taken in 70 connection with the accompanying drawings, it is thought that the construction, the manner of using, and the many advantages of my invention will be readily understood, and a further explanation is therefore deemed un- 75 necessary.

While I have described my invention as applied to a dress-suit case, I wish it understood that I do not limit myself to this application, since the closure may be used upon various 80 boxes, receptacles, and the like. Furthermore, it will be understood that various changes in the form, proportion, and the minor details of construction may be resorted to without departing from the principle or 85 sacrificing any of the advantages of this invention.

Having thus described my invention, what I claim as new, and desire to secure by Letters Patent, is—

A body for traveling-cases and the like composed of inner and outer layers of sheet material, the upper edge of the outer layer forming a rim or support for the edge of a cover to rest upon, the upper edge of the inner 95 layer extending above said rim and bent in-

ward at an oblique angle to form a beveled portion and having its upper edge folded inwardly and downwardly, and an intermediate layer extending down between said inner and outer layers below the rim and projecting upwardly above the rim to form an outer lining for the said beveled portion of the inner layer, said upwardly-projecting portion of the intermediate layer being bent over and around the fold of the said beveled portion of the inner layer and having its free edge bent up between

the oblique portion and fold, thus interlocking therewith to form a stiffened edge, substantially as described.

In testimony whereof I have signed my name 15 to this specification in the presence of two subscribing witnesses.

WILLIAM D. CHASE.
